METHOD OF CORRUGATING CYLINDERS

Albert G. Wery, Sunnyside, and Leslie A. Pepple,
Staten Island, N. Y.

Application February 28, 1938, Serial No. 193,188

2 Claims. (Cl. 153—73)

This invention relates to a method of corrugating cylinders and forms a continuation in part of our co-pending application, Serial No. 54,104, filed December 12, 1935, which is now Patent No. 2,112,509, entitled Apparatus for corrugating cylinders.

A primary object of this invention is the provision of an improved method of corrugating cylinders whereby an improved corrugated article is provided.

A further object of this invention is the provision of an improved method of corrugating cylinders wherein a plurality of sections of cylinders may be simultaneously corrugated and secured together by such corrugation.

A still further object is the provision of an improved method of corrugating cylinders whereby any number of corrugated sections may be relatively simply connected.

A still further object is the provision of an improved method of connecting corrugated cylinders.

A still further object lies in the provision of a method whereby one end of the cylinder is left uncorrugated to receive the end of a wholly uncorrugated cylinder or closed end boot and the corrugating process then continued over such overlapped ends whereby the same are corrugated together and the corrugations continued along the second named cylinder, thus providing one continuous series of transverse corrugations through two or more sections of cylinders or through a cylinder section and the open end of a boot, and automatically providing means whereby said sections are secured together by said corrugations. The corrugations are a series of equally spaced transverse corrugations of uniform cross-section.

Other objects and advantages will be apparent as the description proceeds, reference now being had to the figures of the accompanying drawings forming a part of this application and wherein like reference numerals indicate like parts.

In the drawings:

Figure 1 is a side view of our apparatus.

Figure 2 is a partly sectional end view thereof taken on the line 2—2 of Figure 1.

Figure 3 is a detail view partially in section of a plurality of sections of cylinders and an end boot corrugated and secured together in accordance with this invention.

Figure 4 is a view similar to Figure 3 but showing a tapered shell provided with a slip joint.

Figure 5 is a sectional view of a corrugated

pipe or shell open at both ends and provided with a connecting band, and

Figure 6 is a sectional view taken along the line 6—6 of Figure 5.

5 The apparatus for producing cylinders while fully described and claimed in the above mentioned parent application is hereinafter described in some detail in order that the method which comprises the instant invention may be more readily understood. It will be understood by those skilled in the art that the proportions of metal thickness, size of corrugations and other details of construction, as disclosed in the drawings, are for purposes of illustration only and 10 are not critical dimensions.

The reference character 1 refers to a supporting base upon which are suitably rigidly secured the upstanding brackets 2 and 3 and also upon which is suitably secured the I beam supporting 15 member 4. Another supporting bracket 5 is also suitably secured upon the base 1.

Suitably journaled in bearings 6 and 7 in the brackets 2 and 3 respectively, and in the bearing 8 on the bracket 5, is a mandrel shaft 9 provided 20 with an extending circumferentially corrugated mandrel portion 10, the teeth of which are rounded and disposed in spaced relation, on the mandrel.

The opposite end of the mandrel shaft 9 is 25 reduced and is journaled at its extreme end in the bearing 8. Freely rotatable upon the mandrel shaft 9 is a pair of spaced, oppositely disposed bevel gears 11 and 12 meshing with a bevel gear 13 disposed at right angles thereto, and secured 30 upon shaft 13a. Each of the gears 11 and 12 are provided with clutch faces 14 and splined upon the shaft 9 between the gears 11 and 12 are clutch members 15 adapted to selectively engage and be driven by either gear 11 or gear 12 or to occupy the neutral position shown in Figure 35 1. The clutch lever 16 is pivoted as at 17 on one end of the bracket 3 and this lever has suitable means, not shown, for engaging within a groove 19 in the clutch member whereby upon rocking the lever 16 in one direction or another said clutch will be slid along the shaft to engage either of the clutches 14 on the gears 11 and 12.

It will be clear that if the clutch member 15 40 engages the corresponding clutch member on the gear 11, the shaft 9 will be rotated in one direction. If the opposite clutch member 15 engages the corresponding clutch member on the gear 12, the shaft 9 will be rotated in the opposite direction. Also obviously, if the clutch lever 16 is in 45 the neutral position shown in Figure 1, the gears 55

11 and 12 will rotate freely on the shaft 9 and consequently the said shaft with mandrel 10 will be at rest. Any suitable means, not shown, such as an electric motor, may be provided to drive the shaft 13a.

The upper end of the clutch lever 16 is pivotally connected to one end of a rod 20 slidably mounted in journals 21 formed on the tops of brackets 2 and 3 and on the top of a bracket 22 provided at the opposite end of the machine. Handles 23 are provided on the rod 20 at spaced points whereby, an operator may conveniently reach and take hold of one of said handles and slide the rod longitudinally in either direction to actuate the clutch lever.

Adjustable collars 24 are also provided on the rod 20 and adapted to be set in selected positions and secured in such positions by the thumb screws 25. These collars serve as automatic clutch actuating means in a manner which will be described.

Also journaled in the brackets 2 and 3 at a point spaced from and parallel to the mandrel shaft 9 and in substantially the same plane therewith, is a shaft 26 carrying a pinion 27. This pinion meshes with a similar pinion upon the mandrel shaft 9 and also meshes with a gear 29, upon a shaft 30 likewise journaled in the brackets 2 and 3. The opposite end of this splined shaft 30 projects beyond the bracket 2 and is disposed parallel with the mandrel 10, the extreme end being supported in the bracket 22. The gear 29 meshes with a pinion 31 on a shaft 32 also journaled in the brackets 2 and 3 and projecting beyond the bracket 2 and having its opposite end journaled in the bracket 22, the extreme end of such shaft being squared as at 33 to receive a wrench or other tool whereby the same may be rotated by hand. This shaft 32 is screw-threaded as at 34 for a purpose to be described.

Fixedly mounted at the upper ends of the brackets 2, 3 and 22, and extending longitudinally and parallel with the screw shaft 32, the shaft 30, and the mandrel 10, is a supporting cylinder 35 upon which is slidably mounted carriage 36 provided on its upper side with an apertured lug 37 through which passes the clutch rod 20. The carriage 36 is provided with downwardly extending supporting arms 38, the lower ends of which carry a bearing member 39 slidable upon the shaft 30.

Journaled upon the shaft 30 to pivot about the same in spaced relation on opposite sides of the carriage member 39, is a pair of bell crank arms, the upper legs 40 of which converge into a single threaded journal 41 through which is threadably mounted an adjusting screw 42 provided with a hand wheel 43 on its outer end. The opposite legs 44 of the bell crank levers (see Figure 2) extend angularly toward the rear of the machine above the mandrel 10 and support a fixed shaft 45 upon which is rotatably mounted the corrugating tool 46. The extreme rear ends of the legs 44 are connected by a bar 47.

Also rotatably mounted upon the shaft 45 and secured, one at each end, to the corrugating tool 46 are the gears 45a adapted to mesh with similar gears 45b splined upon the shaft 30 to rotate therewith and capable of sliding therealong. These gears 45b are disposed between the pivot points of the bell crank arms 40-40 and 44-44.

Carried upon the rear side of the carriage 36 (see Figure 2) is a cylinder housing 48 within which is disposed a plunger or piston 49. A source of air pressure 50 communicates with the

interior of the housing below the piston whereby upon operation of a suitable valve by the operator to admit compressed air into such housing, the piston is forced upwardly. Connected 5 to the piston 49 and projecting downwardly out of the housing 48 is a rod 51 having a pivotal connection as at 52 with a link 53, the lower end of which is pivoted as at 54 to the tie rod 47.

Suitable resilient means, not shown, forces tie 10 rod 47 downwardly whereby normally bell crank arms 47 and corrugating tool 46 are forced into mandrel engaging position. Obviously however, if the operator admits air pressure into the housing 48 as described, the upward movements of 15 the piston 49 will instantly lift the corrugating tool above the mandrel. The corrugating tool may also be raised above the mandrel, and its pressure against the mandrel adjusted by means of the adjusting screw 42 and hand wheel 43, the inner end of the screw 42 bearing against a lug 59 formed on the carriage 36.

The downwardly depending supporting arms 38 on the carriage 36 are provided with a threaded boss 60 through which passes the lead screw or threaded shaft 34, the threads thereof engaging the threads in said boss whereby rotation of the shaft serves to slide the carriage 36 and the corrugating tool longitudinally of the mandrel 10.

30 The boss 37 on the carriage 36 serves to engage with one of the collars 24, depending upon the direction of travel, when a predetermined length of travel has been reached and move the clutch rod 20 longitudinally to actuate the clutch lever.

35 A section of pipe or cylinder shell is adapted to be loosely mounted upon the mandrel 10 as shown clearly in Figure 1, in position for the corrugating tool 46 to engage thereagainst and for the spiral thread thereof to press the wall of the shell or cylinder into the corresponding corrugations of the mandrel 10 whereby to corrugate such wall. This produces a series of 40 equally spaced transverse corrugations of uniform cross-section. In a normal operation and with the mandrel and corrugating tool rotating, the shell will be rolled around the mandrel and a circumferential corrugation formed therein. A fixed stop member 61 is attached on the supporting beam 4 against which the end of the shell engages.

45 At the outer end of the supporting beam 4 there is provided a suitable bracket 62 supporting a pair of bearing rollers 63 provided with teeth corresponding to the mandrel teeth and thus forming a roller bearing for the projecting end of the mandrel.

50 Suitable means are also provided on supporting beam 4 to prevent the pipe from being forced to one side or the other of the mandrel by the action of the embossing tool.

55 In the corrugating of the pipe the end thereof may be left uncorrugated for a short distance as shown in Figure 1, so as to receive an adjacent uncorrugated cylinder and the over-lapping or telescoping ends are then corrugated together as shown in Figure 3, whereby to secure such ends together and to provide a uniform series of equally spaced transverse corrugations of uniform cross-section throughout the length of one or a plurality of sections. These pipe sections are generally formed slightly tapered which facilitates this telescoping of adjacent ends.

70 In operation the carriage with the corrugating tool is first adjusted longitudinally on the

supporting members 30 and 35 to the desired position with respect to the mandrel for beginning the corrugating operation, this adjustment being made either by hand, by turning the lead screw 34 by means of a suitable tool engaging the squared end 33 thereof, or by power drive from drive shaft 13a, through either bevel bear 11 or 12, shaft 9, pinion 28, pinion 27, gear 29 and pinion 31. The rotation of the lead screw results in longitudinal sliding movement of the carriage 36 and bearing 39 along the supporting members 35 and 30, with consequent sliding and rotative movement of the embossing tool carried thereby. Obviously the corrugating operation may be begun at either end of the mandrel, the latter being rotatable in either direction, as above explained.

With the parts thus set, the corrugating tool is raised above the mandrel, either by operating the hand wheel and screw 42 or by permitting air to enter the cylinder below the piston 49, resulting in rocking the bell crank arms 44 upwardly about their pivot 30 and carrying with them the shaft 45 and embossing tool 46.

An uncorrugated shell is now placed upon the mandrel 10 and slid inwardly on the same until the end of the shell engages the stop 61.

The corrugating tool is now lowered into engagement with the shell and sufficient pressure is exerted by the resilient means to cause the spiral of the corrugating tool to press the wall of the shell or pipe into the corrugations of the mandrel thus forming a series of equally spaced transverse corrugations of uniform cross-section. It may be explained here that the thread of the corrugating tool is spirally disposed, so that as the corrugating proceeds, the corrugating tool adopts a screw action in following the non-spiral grooves of the mandrel.

The collars 24 are now adjusted on the clutch rod 20 so as to be engaged by the boss 37 on the carriage 36 when such carriage has reached a predetermined position with respect to the end of the shell 67, preferably when the corrugating tool has come within a short distance of the end of the shell.

With the drive shaft 13a rotating, the clutch rod is now actuated to cause rotation of the mandrel shaft 9, shaft 30 and lead screw 32, in the desired direction. The shell 67 rolls around the mandrel 10 between the said mandrel and the embossing tool and is corrugated in the manner shown, the corrugating tool and carriage being simultaneously moved along by the lead screw 34. The shell is prevented from swinging outwardly or becoming displaced by means of the roller supports 66 engaging the inner wall thereof. The corrugating tool and the mandrel rotate in opposite directions.

When the corrugating operation has reached the desired point adjacent the end of the shell section, the clutch 15 is moved into neutral position either manually by means of the handles 23 or automatically by the boss 37 engaging one of the collars 24, thus stopping the further rotation of the mandrel and corrugating tool. Of course, in some instances, as desired, the corrugating of a section of shell may be carried to the extreme end thereof.

The corrugating tool and carriage is now raised above the mandrel in the manner previously described and the shell removed from the mandrel, this removal being wholly unhindered and unimpaired by any part of the machine and requiring no other disconnection of parts. The section is

simply lifted and pulled freely from the mandrel. Now, if desired, a new and uncorrugated section, such as shown at 81 in Figure 3, may be engaged together at their ends by telescoping the said ends for a short distance, the normal taper usually provided on the shells making this a convenient and easy operation.

Assuming that the embossing or corrugating operation has proceeded from left to right in Figure 1, in the operation just described, the new shell is now placed upon the mandrel first, with its inner end engaging against the stop 61 and with its opposite joined end and the section just corrugated supported upon the mandrel.

The corrugating tool and its associated carriage are now lowered into engagement with the previously corrugated section adjacent the termination of the corrugations thereof and the clutch moved to drive the parts in the same direction as before. The corrugating proceeds as before through the overlapping ends of the two sections and continues until the end of the previously uncorrugated section or a predetermined point short of the end thereof has been reached.

Thereupon the corrugating tool and carriage are again raised, either manually or automatically by the other collar 24, causing the parts to stop. Obviously this can continue until as many sections of shell as desired are corrugated and secured together to the end or ends of the end-most sections.

To sum up, the method herein described relates to making tubes of substantial length in which the tubes are composed of a plurality of sections formed with a continuous series of equally spaced transverse corrugations of uniform cross-section. The steps of forming these tubes consist in corrugating a section of sheet metal pipe except for an extreme end portion thereof and thereafter telescoping a second uncorrugated section into the uncorrugated end of the first section. Thereafter the telescoping sections are interlocked by continuing the uniform corrugations in the telescoped tube sections and the corrugations continued throughout the length of the additional tubes in a direction toward the free end of the additional sections. The first section may be either a tube section or an end boot as disclosed in the drawings.

Having reference now to Figure 3 there is shown a corrugated shell 67 corrugated, in accordance with the methods of this invention, in sections, which sections are secured by corrugations, as at 80. To the lowermost of sections 67 is secured an end boot 81 provided with a bottom portion 82 secured to the lowermost of sections 67 in the manner previously described.

In connection with joining the sections 67, interiorly of boot 81, is placed a light gauge steel pan 83 in order to reenforce the end section when driving the boot into the ground. If desired a hole 84 may be positioned in end portion 82 of boot 81 and a corresponding hole 84 may be positioned in pan 83 in order that the composite structure may be connected with a pipe or lower section of wood or other material to form a composite pile.

Figure 4 discloses a tapered pile made in accordance with this invention comprising a plurality of sections 90 and an end boot 91. Certain of sections 90 may be connected by corrugations, as at 92, in accordance with the principles of this invention and certain other sections may be connected as by a slip joint 93 in order that com-

posite sections of a pile may be transported to the locality at which it is desired that they be used whereupon the slip joint 93 permits ready assembly of a plurality of sections. A reenforcing pan 94 may be positioned in the boot of end section 91 for a purpose similar to that of pan 83.

Figure 5 discloses a plurality of pipe sections 100 of particular utility for use as a culvert. Certain of sections 100 are connected by means of the corrugation in the manner previously described as at 101, and certain others may be connected, as by means of a conventional connecting band 102 provided with angles 103 through which may be passed clamping bolts 104 in a known manner.

Now from the foregoing it will be seen that there is herein provided a method of corrugating cylindrical pipes as well as a method of joining certain of the corrugated pipes or cylinders which accomplishes all the objects of this invention and others including many advantages of great practical utility.

As many embodiments may be made of the inventive concept herein set forth and as many modifications may be made in the embodiment described and shown in the accompanying drawings it is to be understood that all matter herein set forth and shown is to be interpreted merely as illustrative and not in a limiting sense.

We claim as our invention:

1. The method of making tubes of substantial length wherein the tubes are composed of a plurality of sections and are formed with one continuous series of equally spaced transverse corrugations of uniform cross-section, comprising the steps of forming such corrugations in a first section except for an extreme end portion thereof, telescoping a second uncorrugated section into the uncorrugated end of the said first section,

thereafter progressively forming interlocking corrugations of the original uniform cross-section and spacing simultaneously in both of the telescoped tube sections throughout their length in a direction toward the free end of the second section, and thereafter progressively forming corrugations of the original uniform cross-section and spacing in the remainder of the second section in a direction toward the free end of the second section.

2. The method of making tubes of substantial length wherein the tubes are composed of a plurality of sections and are formed with one continuous series of equally spaced transverse corrugations of uniform cross-section, comprising the steps of forming such corrugations in a first tube section except for the extreme end portions thereof, telescoping an end boot into an uncorrugated end of said first tube section, then progressively forming interlocking corrugations of the original uniform cross-section and spacing simultaneously in both of the telescoped sections throughout their length in a direction toward the free end of the boot, then telescoping a second tube section into the remaining uncorrugated end portion of the said first tube section, then progressively forming interlocking corrugations of the original uniform cross-section and spacing simultaneously in both of the telescoped sections throughout their length in a direction toward the free end of the second section, and thereafter progressively forming corrugations of the original uniform cross-section and spacing in the remainder of the second section in a direction toward the free end of the second tube section.

ALBERT G. WERY.
LESLIE A. PEPPLER.
